REUSABLE SCREW TOP CAN

Filed July 6, 1950

UNITED STATES PATENT OFFICE

2,602,565

REUSABLE SCREW TOP CAN

John E. Regan, Elmhurst, N. Y.

Application July 6, 1950, Serial No. 172,303

1 Claim. (Cl. 220—29)

1

The present invention relates to containers of the "tin-can" type and has for its principal objective the provision of an improved screw type end closure for the can body thus rendering the can reusable for general purposes and especially for food storage since the can becomes hermetically sealed when the closure member is screwed tightly in place over the open can end.

Another object is to provide an improved can construction having a removable end cap, in which the periphery of the can at the open, cap end is beaded over in a radially outward direction thereby to establish a seat for a sealing gasket and also provide a smooth surfaced mouth that makes it easier to pour out the can contents when the latter are liquids.

Another object is to provide a reusable can that presents a substantially smooth interior surface, e. g. truly cylindrical, thus making it easier to clean and thereby decreasing the possibility of food contamination which might result from inadequate cleaning of the can interior.

The foregoing as well as other objects and advantages inherent in the invention will become more apparent from the following detailed description of a preferred can construction embodying the invention together with the accompanying drawings in which:

Fig. 1 is a view in side elevation of the can with the end closure cap in place;

Figs. 2 and 3 are top and bottom plan views, respectively; and

Fig. 4 is a view in central vertical section through the upper end of the can and cap, it being noted that this view is drawn to a much greater scale than the other views in order to show the inventive structural features more clearly, and moreover is limited to those portions of the cap and can body adjacent the perimeters thereof.

With reference now to the drawing, the main body of the can 1 can be generally conventional, the particular construction illustrated in Fig. 1 being of tin plate with the usual longitudinally extending lap and lock seam 2 and bottom end closure plate 3.

The upper end of the can shown in Fig. 4 is however quite unconventional and in fact unique, including a collar or sleeve 4 threaded intermediate its ends at 4a, the sleeve being so dimensioned as to make a snug press fit with the outer face of the can body 1. As a practical matter the threads 4a are preferably rolled on the sleeve 4 before the latter is slid into place over the upper, open end of the can. The upper and lower unthreaded

portions 4b, 4c of the sleeve extend for a substantial distance along the can body to establish a firm grip upon the latter while the intermediate threaded portion is preferably spaced somewhat radially outward from the can body in order to accommodate a large diameter cap to make for easier screwing on and off of the cap by hand. Of course, if the diameter of the can be sufficiently large already, the intermediate threaded portion of the sleeve may be set in closer to the can body.

The lower end of the sleeve is stopped by a plurality of small bosses 5 pressed out from the can body and the upper end is beaded over at 4d in a radially outward direction. The sleeve 4 may also be spot welded if desired to the can body to improve the connection between the two thereby decreasing the possibility of the sleeve rotating on the can body when the cap is screwed on.

20 Such welds are indicated at 6.

The upper end of the cylindrical can body is beaded over the beaded end 4d of the sleeve at 1a, it being noted in particular that the bead 1a is also formed by rolling the rim of the can in a radially outward direction. The circular bead 1a is thus external rather than internal with respect to the can body and permits the latter to present a smooth surfaced mouth for easier pouring off of liquid contents from the can.

30 Moreover the smooth mouth is easier to keep clean and therefore more sanitary.

The end closure member for the can is seen to be a cap 7 preferably metal having a threaded cylindrical rim 7a for engagement with the threads 4a on the sleeve. A pair of ribs 7b, 7c concentric with the cap center are formed at the under side of the cap end such as by die pressing from the upper side. The outer rib 7b, preferably located substantially in radial alignment with the circular bead 1a on the can end, is completely circular. The inner rib 7c, located substantially midway between the cap center and its rim, is however broken at diametrically opposite points by a pair of bosses 7e, pressed outwardly from the cap material.

As seen clearly from Fig. 4, the inner rib 7c constitutes a centering device for a plate 8 having a central cylindrical die pressed recess 8a into which the inner rib 7c enters from the upper side 50 of the plate. The central recessed portion 8a, die pressed into the upper side of the plate also produces at the under side a cylindrical boss 8b that forms a centering device for a sealing ring 9 that seats on the can bead 1a.

55 Operation of the closure is believed to be self-

explanatory. However a brief summary will be conducive to a clearer understanding of the structure. Threaded sleeve 4 being integral with the rest of the can body, ring 9 will be pressed upon its seat, bead 1a, as cap 7 is screwed down by hand upon sleeve 4 thus hermetically sealing the interior of the can. Moreover, since plate 8 is rotatable upon cap 7, there is no tendency for the sealing ring 9 to rotate while the cap is being screwed down thus eliminating any chance of the ring being twisted off its seat to establish a leakage path for air into the can between the seat 1a and under face of ring 9. Rather once the ring 9 and plate 8 are seated, the circular rib 7b on the cap will slide in surface engagement with plate 8 as the cap is screwed down, the plate remaining stationary, and the rib 7b applies principally an axially downward force to plate 8 which is of course transmitted to sealing ring 9 thus establishing a high degree of sealing pressure with the can bead 1a which itself is reinforced by the sleeve bead 4d. When removing the cap, the latter can easily be started by inserting a knife blade or the like between the projections 1e and applying a torque to the blade about the axis of the can.

The pre-threaded sleeve 4 may be applied to the can body in various ways but the following described method is deemed the most practical.

Initially, the upper end of the can 1 from which is ultimately formed the bead 1a is plain edged. This permits the sleeve to be forced down upon the can body from above in a press until the former is stopped by the bosses 5. A beading tool is then used to turn the bead 1a over the pre-formed bead 4a on the sleeve. Alternatively, the upper end of sleeve 4 may also be plain edged in which case, both beads 4a and 1a could be formed simultaneously by the beading tool. The spot welds 6, if used, are then applied 40 by suitable electric welding apparatus.

Having thus described my invention, it being understood that the illustrated embodiment thereof is to be considered typical only and that minor structural variations are possible without 45 however departing from the spirit and scope of

the invention as defined in the appended claim, what I claim is:

A reusable metallic can comprising a cylindrical can body of uniform diameter closed at one end, a threaded sleeve surrounding and secured to said can body at the other end thereof, said other can end being beaded over a bead at the end of said sleeve in a radially outward direction to form a smooth pouring lip reinforced by the bead on said sleeve, a threaded cap adapted to be screwed onto the threaded portion of said sleeve, and a sealing ring seated on said lip and pressed into contact therewith by said cap, said cap including a pair of radially spaced arcuate ribs 15 raised upon the inside surface thereof concentrically with the cap center and further including a pressure plate having an offset central portion establishing a central circular recess at the upper side thereof receiving the innermost rib on 20 said cap for centering said plate relatively to said cap and a central circular boss at the under side thereof having a diameter substantially equal to the internal diameter of said sealing ring for receiving and centering the ring on said plate, the outermost rib on said cap being of approximately the same diameter as the said pouring lip and transmitting pressure to said ring through said plate substantially in line with said lip as said cap is screwed on to said sleeve.
